UNITED STATES PATENT OFFICE.

JEFF BAKER, OF WARDELL, ARKANSAS.

PERCUSSION MUSICAL INSTRUMENT.

1,168,843.

Specification of Letters Patent.

Patented Jan. 18, 1916.

Application filed June 6, 1914. Serial No. 843,473.

To all whom it may concern:

Be it known that I, JEFF BAKER, a citizen of the United States, residing at Wardell, in the county of Mississippi and State of 5 Arkansas, have invented certain new and useful Improvements in Percussion Musical Instruments, of which the following is a specification, reference being had to the accompanying drawings.

10 This invention relates to certain improvements in percussion musical instruments, and an object of the invention is to provide a novel and improved instrument including a sound chest wherein the opposite ends thereof are open.

15 The invention consists in the details of construction and in the combination and arrangement of the several parts of my improved musical instrument whereby certain 20 important advantages are attained and the device is rendered simpler, less expensive and otherwise more convenient and advantageous for use, all as will be hereinafter more fully set forth.

25 The novel features of the invention will be carefully defined in the appended claims.

In order that my invention may be the better understood, I will now proceed to describe the same with reference to the accompanying drawings, wherein—

30 Figure 1 is a view in top plan of an instrument constructed in accordance with an embodiment of my invention; Fig. 2 is a sectional view taken substantially on the line 35 2—2 of Fig. 1, looking in the direction of the arrow; Fig. 3 is a sectional view taken substantially on the line 3—3 of Fig. 1, looking in the direction of the arrow; and Fig. 4 is a view in plan of the hammer herein 40 included, for striking the sonorous members.

45 As disclosed in the accompanying drawings, A denotes a sound chest comprising the spaced imperforate members 1, herein disclosed as substantially rectangular in form and maintained in their relative spaced 50 positions through the medium of the interposed elongated blocks 2. In practice, I find it especially desirable that the members 1 and the blocks 2 be formed of hard wood and that the abutting portions thereof be connected one with the other through a suitable adhesive together with a plurality of clamping bolts 3, as is clearly shown in the accompanying drawings. I have found 55 that it is essential that the clamping bolts 3

be employed as with the use of adhesive alone, the best results cannot be obtained. By the construction of the sound chest herein set forth, it will be perceived that such chest comprises a hollow body open at its ends. 60

Operatively engaged with one of the members 1 are the sonorous members 4, tuned to afford a chromatic scale and herein disclosed as positioned one relative to the other in a manner similar to the arrangement of 65 the keys of an ordinary piano.

As herein embodied, each of the sonorous members 4 comprises an elongated strip of material preferably brass wire or steel wire heavily coated with copper. One extremity 70 of the strip is formed into an eye 5 to afford a suitable anchoring means and, as herein disclosed, such eye has projecting therethrough the extremity of a headed bolt 6, the head whereof is disposed against the 75 under face of the member 1 while the upper or threaded extremity of such bolt is engaged by the clamping nuts 7 and 8, the nut 8 serving as a jam nut.

The remaining portion of the member 4 is 80 coiled with the convolutions 9 thereof positioned in substantially the same plane, with the smallest coil located centrally of the member, as is believed to be fully shown in the accompanying drawings. I have found 85 in practice that the requisite pitch may be imparted to the sonorous member 4 by cutting off the free extremity of the strand until the desired pitch is created.

In order that the instrument may be 90 played with convenience and facility, I find it desirable to dispose longitudinally of the sounding member or chest A the strip 12 interposed between the two rows of members 4 and provided thereon with the requisite 95 indications 14 to denote the pitch of the member. I also find it of advantage in some instances to have a plurality of members 4 arranged in close proximity one to the other and of the same pitch so that the requisite 100 blow from the hammer B may be facilitated or, if desired, the clustered members 4 may be of different pitches so that a chord or harmony may be sounded at one blow. When the members 4 are disposed in this coacting 105 relation, I find it of advantage to have the eye of one member oppositely related with the eye 5 of the coacting member.

While I have hereinbefore set forth my invention as adapted to be employed in con- 110

nection with a hammer adapted to be held in the hand of the player, I wish to state that my device may be employed in connection with a conventional piano structure whether of a toy type or otherwise, and I have found in practice that it can be employed in such instances with equal facility.

From the foregoing description, it is thought to be obvious that a percussion musical instrument constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and for-

mation of the several parts herein shown in carrying out my invention in practice.

I claim:

In combination, a sound chest comprising 25 spaced normally imperforate members, elongated blocks interposed between the members adjacent the longitudinal margins thereof, the opposite ends of the chest being open, an adhesive for connecting the blocks 30 and members, bolts passing through the members and the blocks to afford an additional means for maintaining the same in assembled relation, and a sonorous member secured directly to one of the spaced members of the chest. 35

In testimony whereof I hereunto affix my signature in the presence of two witnesses.

JEFF BAKER.
